SHIP REPAIR EQUIPMENT

John H. Segel, Glendale, Calif.

Application October 12, 1936, Serial No. 105,276

10 Claims. (Cl. 114—222)

My invention relates to ship repair and submerged hull maintenance equipment, and has for its principal object the provision of a relatively simple, practical and easily handled apparatus 5 that includes a flexible sheath for the hulls of vessels, and also a floating crib that combines with the sheath and which enables the hulls of vessels to be scraped, painted, overhauled and repaired without the necessity of placing the ship 10 in dry-dock.

Further, my improved ship's hull repair and maintenance equipment enables workmen to conveniently reach any portion of the hull below the water while making inspections, repairs, the 15 changing of propeller blades, or repairs and adjustments to the rudder.

The repair maintenance equipment may be used at any time, but it is particularly intended for use while the equipped ship is docked for the 20 loading or discharge of its cargo, thus eliminating the loss of time in making repairs upon ships that move on schedule.

A further object of my invention is to provide in a ship repair and submerged hull maintenance 25 equipment a sheath or cover for the entire lower portion of the ship's hull, which sheath or cover comprises a number of detachably connected sections of flexible waterproof material, such as heavy canvas or rubberized fabric, said sheath being supported by lines from the ship's rail and the crib that is used in connection with the flexible waterproof sheath comprising buoyant members that are arranged on the exterior of the waterproof sheath and having associated therewith a 30 flexible skeleton structure that is interposed between the waterproof sheath and the surface of the hull of the vessel in order to provide ample working space for the workmen engaged in making inspections, repairs and the like.

With the foregoing and other objects in view, 35 my invention consists in certain novel features of construction and arrangement of parts that will be hereinafter more fully described and claimed and illustrated in the accompanying drawing, in 40 which:

Fig. 1 is a side elevational view of a ship and showing my improved repair and maintenance equipment in position thereupon.

Fig. 2 is a vertical section taken approximately 50 on the line 2—2 of Fig. 1.

Fig. 3 is an enlarged detail section taken approximately on the line 3—3 of Fig. 1.

Fig. 4 is an enlarged detail horizontal section taken on the line 4—4 of Fig. 1.

Fig. 5 is a perspective view of portions of the 55

adjacent ends of sections of the waterproof sheath and showing the construction of the waterproof joint that is provided between the said sections.

Fig. 6 is a detail view of a portion of a flexible skeleton structure that is connected to the upper portion of the crib and which extends downwardly between the waterproof sheath and the hull of the vessel.

Referring by numerals to the accompanying drawing which illustrates a preferred embodiment of my invention, 10, 10 designates large sections of flexible waterproof material, for instance heavy closely woven canvas, or fabric that has been treated to render it waterproof, said sections being of sufficient length to cover the 15 bottom of a vessel and to extend upwardly on the sides thereof to a plane wholly above the water-line and the width of said sections may vary as desired.

Seated in the upper edges of the sections of 20 waterproof material are eyelets 11 in which are secured the lower ends of lines 12, the upper ends thereof being provided with hooks 13 that engage over the ship's rail.

The vertical edges of the sections of waterproof material 10 are embedded in strips 14 of rubber or rubber composition and the free edge of the strip on one end of each sheet terminates in a rib or bead 15 that is preferably round in cross section and which is adapted to engage in 30 a channel 16 that is formed on the free edge of the strip 14 on the next adjacent section 10.

Thus when the waterproof sections 10 are assembled to cover the lower portion of the hull of a vessel, each rib or bead 15 is inserted lengthwise into the adjacent channel 16, thus providing a flexible and at the same time a waterproof joint between the ends of the sections 10. Inasmuch as the rib or bead 15 and the channel 16 are formed of rubber they will flex or bend readily and conform to the transverse curvature of the hull of the vessel.

The outer ends of the sections 10 that are positioned adjacent the ends of the hull are both provided with ribs or beads 15 that slide lengthwise 45 into channels 17 that are formed in a heavy strip 18 of rubber, thus providing waterproof joints between the vertical edges of the waterproof sections 10 at both ends of the hull (see Fig. 4).

The crib that is utilized in connection with the sheath formed by the waterproof sheets 10 is preferably formed in identical sections, any number of which may be assembled to provide a crib of the desired length, and each section 55

comprises a pair of hollow members 19 and 20 that are formed of sheet-metal or the like.

The member 20 of each section of the crib has less thickness than the member 19 and when 5 the crib is applied to a vessel that is tied up to a dock, such construction conserves space between the vessel and the vertical face of said dock.

To protect the relatively thin member 20 of 10 each crib section, a suitable buffer 21 is applied to the outer face of said member 20. The members 19 and 20 are made water- and airtight in order that they may be filled or partially filled with water when they are submerged so as to 15 be positioned beneath the hull of a vessel and after the water in the crib has been pumped out said members are rendered buoyant, thereby tending to maintain the crib against the underside of the hull.

20 The lower portions of the members 19 and 20 are extended toward each other, as designated by 22, and these extensions are positioned beneath the hull of the vessel when the crib is applied for use.

25 Connecting the ends of the crib members 19 and 20 are rails 23 that are adjustably connected to said crib members by bolts 24 that pass through apertures in said rails, and as a result of this construction the crib members 19 and 20 30 may be moved toward or away from each other and firmly secured in their adjusted positions so as to accommodate vessels' hulls of different widths.

The upper ends of the hollow crib members 19 35 and 20 are provided with openings 25 normally closed by plugs or caps 26, thus providing means for admitting water to the crib members, or to permit said water to be pumped from said members.

40 Associated with each crib member 22 and arranged on the inner side thereof, is a jointed skeleton framework which, when the equipment is in use, occupies a position between the waterproof sheath and the surface of the hull of the 45 vessel. This structure is illustrated in Figs. 2 and 6, and it comprises a series of substantially inverted L-shaped members, each of which is composed of a horizontally disposed portion 27 and an upright or inclined portion 28.

50 The end of the horizontal portion 27 of the upper one of said inverted L-shaped members is connected by a suitable hinge or pivot 29 to the upper inner corner of the adjacent crib member 22, and each of the succeeding lower sections 55 of this structure has the end of its horizontal leg connected by a hinge or pivot 30 to the lower end of the vertical or inclined leg 28 of the next adjacent upper member of the structure.

Thus a flexible skeleton structure is provided 60 which occupies a position between the sheath and the hull of the vessel, thereby holding the sheath away from the hull to provide working space and scaffolding or boards may be applied to the horizontal members of this structure in order to provide supports for the workmen. This particular structure is made in sections that are hinged or pivoted to each other in order that the structure will conform to the various cross sectional contours of the hull of a vessel.

70 While not in use, the waterproof sheath may be folded together and packed into the space between the crib members 22 and the flexible skeleton structures on the inner sides thereof, and to apply the sheath to the hull, the crib containing the sheath is submerged in front or to the

rear of the hull and then moved longitudinally of the hull and the sheath is manipulated so that it is unfolded as the crib moves lengthwise, thus leaving the sheath positioned beneath and to the sides of the hull and suspended by the lines 5 12.

After the ends of the sheath are connected by the flexible strips 13, the water within the sheath is pumped out, after which the crib is moved lengthwise of the hull of the vessel to the desired position where inspection or repairs are to be made, and after the skeleton framework has been properly positioned between the sheath and the hull of the vessel, the water is pumped out of the crib to render the same buoyant so it will 15 rise to the desired elevation.

If desirable or necessary, panels 27a of wood or metal may be secured to the rear or outer portion of each of the inverted L-shaped members to serve as stays to prevent the canvas or flexible 20 waterproof material from being pressed too far inwardly between said members by the pressure of the water against the outer face of said canvas (see Fig. 6).

Thus it will be seen that I have provided a 25 ship repair and submerged hull maintenance equipment that is relatively simple in construction, capable of being readily applied to or removed from the hull of a ship or vessel, and said equipment enabling the hulls of ships to be 30 scraped, painted, overhauled and repaired without the necessity for placing the vessels in dry dock.

It will be understood that minor changes in the size, form and construction of the various 35 parts of my improved ship repair and submerged hull maintenance equipment may be made and substituted for those herein shown and described without departing from the spirit of the invention, the scope of which is set forth in the appended claims.

I claim as my invention:

1. In a ship repair and submerged hull maintenance equipment, a sheath for covering the lower portion of the hull of the ship, said sheath comprising a plurality of sections of flexible wa- 45 ter-proof material arranged end to end, joints between said sections transversely disposed relative to the ship's hull to which the equipment is applied, comprising a strip of flexible material secured to one end of each sheath section, 50 said flexible section being provided with a longitudinally disposed channel, the opening into which channel is narrower than the inner portion of said channel, a strip of flexible material secured to the other end of each sheath section, 55 the outer edge of which last-mentioned strip of flexible material terminates in a rib that is adapted to be removably seated in the channel in the edge of the next adjacent sheath section.

2. In a ship repair and submerged hull maintenance equipment, a sheath for covering the lower portion of the hull of the ship, said sheath comprising a plurality of sections of flexible wa- 65 ter-proof material, arranged end to end joints between said sections transversely disposed relative to the ship's hull to which the equipment is applied, a flexible rib secured to one end of each sheath section, a flexible tubular socket on the other end of each section, which socket is adapted to receive said flexible rib and the diameter of which rib is greater than the opening of said tubular socket.

3. In a ship repair and submerged hull maintenance equipment, a sheath for covering the lower portions of the hull of the ship, said sheath 70

- comprising a plurality of sections of flexible water-proof material, arranged end to end joints between said sections transversely disposed relative to the ship's hull to which the equipment 5 is applied, flexible water-proof joints between the ends of said sections, each joint comprising a strip of flexible material secured to one end of each sheath section, said flexible section being provided with a longitudinally disposed channel, 10 the opening into which channel is narrower than the inner portion of said channel, a strip of flexible material secured to the other end of each sheath section, the outer edge of which last-mentioned strip of flexible material terminates 15 in a rib that is adapted to be removably seated in the channel in the edge of the next adjacent sheath section.
4. In a ship repair and submerged hull maintenance equipment, a sheath for covering the 20 lower portion of the hull of the ship, said sheath comprising a plurality of sections of flexible water-proof material, arranged end to end, joints between said sections transversely disposed relative to the ship's hull to which the equipment 25 is applied, comprising a flexible rib on one end of each section, a tubular socket on the other end of each section, which socket is adapted to receive said flexible rib, the openings in the tubular socket being narrower than the diameter of the rim that is inserted in said socket and means providing a flexible water-proof joint between the outer ends of the end sections of 30 said sheath.
5. In a ship repair and submerged hull maintenance equipment, a sheath composed of flexible water-proof material arranged to cover the lower portion and sides of a ship's hull, buoyant crib members arranged on opposite sides of said sheath, flexibly connected skeleton members sustained from the upper portion of said crib members and extending downwardly between the sheath and hull of the ship and a panel carried by each skeleton member. 35
6. In a ship repair and submerged hull maintenance equipment, a sheath composed of flexible material arranged to cover the lower portion and sides of a ship's hull, buoyant crib members arranged on opposite sides of said sheath, flexibly connected members sustained from the upper portions of said crib members and extending downwardly between the sheath and hull of the ship, a panel carried by each of said flexibly connected members and means for adjustably connecting the lower portions of said crib members. 45
7. In a ship repair and submerged hull maintenance equipment, the combination with a sheath of flexible water-proof material arranged 50 to cover the lower portion and sides of the hull of a ship, of crib members positioned adjacent the sides of said sheath, said crib members being provided with water chambers and openings for the inlet and outlet of water, flexibly connected skeleton frames sustained from the upper portions of said crib members and extending downwardly between the sheath and the hull of the ship and a panel carried by each of said flexibly connected members. 55
8. In a ship repair and submerged hull maintenance equipment, the combination with a sheath of flexible water-proof material arranged to cover the lower portion and sides of the hull of a ship, of crib members positioned adjacent the sides of said sheath, said crib members being provided with water chambers and openings for the inlet and outlet of water, flexibly connected skeleton frames sustained from the upper portions of said crib members and extending downwardly between the sheath and the hull of the ship, a panel carried by each of said flexibly connected members and means adjustably connecting the lower portions of said crib members and holding them in spaced relation. 60
9. In a ship repair and submerged hull maintenance equipment, a pair of crib members arranged to occupy positions adjacent the sides of a ship's hull adjustable means connecting the lower portions of said crib members, said crib members being provided with water chambers and with openings for the admission and discharge of water, flexibly connected skeleton frames suspended from the upper portions of said crib members and extending downwardly adjacent the inner faces of said crib members, a panel carried by each skeleton frame, a flexible sheath of waterproof material arranged between said skeleton frames and the inner faces of said crib members. 65
10. In a ship repair and submerged hull maintenance equipment, pairs of crib members arranged to occupy positions adjacent the sides of a ship's hull, said crib members being provided with water chambers and with openings for the admission and discharge of water, flexibly connected skeleton frames suspended from the upper portions of said crib members, and extending downwardly adjacent the inner faces of said crib members, a panel carried by each skeleton frame, adjustable means for connecting the lower portions of said crib members to hold the same in spaced relation and a sectional sheath of flexible waterproof material arranged between said skeleton frames and the inner faces of said cribs. 70

JOHN H. SEGEL.
